(57) **CLAIM**

The ornamental design for an attachment interface for a mower blade, as shown and described.

DESCRIPTION

FIG. 1 is a perspective view of an attachment interface for a mower blade showing our new design according to an embodiment;

FIG. 2 is a bottom view of the attachment interface for a mower blade of FIG. 1;

FIG. 3 is an exploded perspective view of the attachment interface for a mower blade of FIG. 1;

FIG. 4 is a perspective view of a blade portion of the attachment interface of FIG. 1;

FIG. 5 is a bottom view of the blade portion of the attachment interface of FIG. 4;

FIG. 6 a top view of the blade portion of the attachment interface of FIG. 4;

FIG. 7 is a perspective view of a mower portion of the attachment interface of FIG. 1;

FIG. 8 is a first side view of the mower portion of the attachment interface of FIG. 7;

FIG. 9 is a second side view of the mower portion of the attachment interface of FIG. 7;

FIG. 10 is a top view of the mower portion of the attachment interface of FIG. 7;

FIG. 11 is a bottom view of the mower portion of the attachment interface of FIG. 7;

FIG. 12 is a perspective view of an attachment interface for a mower blade showing our new design according to another embodiment;

FIG. 13 is a bottom view of the attachment interface for a mower blade of FIG. 12;

FIG. 14 is an exploded perspective view of the attachment interface for a mower blade of FIG. 12;

FIG. 15 is a perspective view of a blade portion of the attachment interface of FIG. 12;

FIG. 16 is a bottom view of the blade portion of the attachment interface of FIG. 15;

FIG. 17 is a top view of the blade portion of the attachment interface of FIG. 15;

FIG. 18 is a perspective view of a mower portion of the attachment interface of FIG. 12;

FIG. 19 is a first side view of the mower portion of the attachment interface of FIG. 18;

FIG. 20 is a second side view of the mower portion of the attachment interface of FIG. 18;

FIG. 21 is a top view of the mower portion of the attachment interface of FIG. 18; and,

FIG. 22 is a bottom view of the mower portion of the attachment interface of FIG. 18.

(Continued)

The broken lines illustrate unclaimed portions of the attachment interface for a mower blade and form no part of the claimed design.
